FISHING ROD RACK

Stuart Y. Fujinami, 2842 S. Norton Ave.,
Los Angeles, Calif. 90018

Filed Jan. 7, 1971, Ser. No. 104,835

Term of patent 14 years

Int. Cl. D6—04, 06

U.S. Cl. D6—114

FIG. 1.

FIG. 2.

FIG. 3.

FIG. 4.

FIG. 1 is a perspective view of a fishing rod rack embodying my new design;

FIG. 2 is a front elevational view thereof;

FIG. 3 is a side elevational view thereof; and

FIG. 4 is a top plan view thereof.

The broken lines are for illustrative purposes only.

I claim:

The ornamental design for a fishing rod rack, as shown and described.
